(57) **CLAIM**

The ornamental design for a compression device, as shown and described.

DESCRIPTION

FIG. 1 is a top, left, front perspective view of an embodiment of a compression device embodying our new design;
FIG. 2 is a top, right, rear perspective view thereof;
FIG. 3 is a left side elevational view thereof;
FIG. 4 is a right side elevational view thereof;
FIG. 5 is a front elevational view thereof;
FIG. 6 is a rear elevational view thereof;
FIG. 7 is a top plan view thereof; and,
FIG. 8 is a bottom plan view thereof.

In the drawings, the broken lines depict unclaimed subject matter only and form no part of the claimed design. The dash-dot-dash lines represent the boundaries of the claimed design. The dash-dot-dash lines in the figures illustrate the portions of the design that form no part of the claim.
